UNITED STATES PATENT OFFICE.

WILLIAM R. ORMES, OF WALTHAM, MASSACHUSETTS.

COMBINED PUNCH AND COUNTERSINKING MACHINE.

1,342,865.

Specification of Letters Patent.

Patented June 8, 1920.

Application filed April 16, 1919. Serial No. 290,485.

To all whom it may concern:

Be it known that I, WILLIAM R. ORMES, of Waltham, in the county of Middlesex and State of Massachusetts, a citizen of the 5 United States, have invented a new and Improved Combined Punch and Countersinking Machine, of which the following is a specification.

The punching and finishing of a screw 10 hole in a metal plate is usually the result of two operations performed by two machines, viz: a press-carrying punch by which the hole is first made, and second, the cutting of a countersink to receive the head of a screw, 15 this being done upon a separate machine.

My present invention relates to a combination machine whereby both of these operations may be performed without removing the work.

20 My invention will be understood by reference to the drawings, in which—

Figure 1 is a side view, and

Fig. 2 is a horizontal section on line 2—2 of Fig. 1;

25 Fig. 3 being a side elevation of the working mechanism in punching position, and

Fig. 4 a vertical sectional view of the same taken during the countersinking operation.

The preferred embodiment of my invention 30 is shown in the drawings mounted on a press of ordinary character—a type of machine so well known that its further description is unnecessary except to say that it comprises a bed A and a vertically-movable head B. On the bed A is mounted a table C carrying a suitable die c of usual character. C¹⁰ is a separator attached to the table C at its rear end, c¹⁰ its front end forming an overhang.

40 To the part C¹⁰ of the separator are pivoted as at c² two arms or channel irons C² which are connected at their outer or free ends by an angular crossbar c³ and are held down by springs C³ attached at their rear ends to the part c¹⁰. The crossbar c³ serves 45 as a clamp to hold the work D against the table C.

As the punch is lifted out of the work the work will be held by the overhang and it 50 and the clamp will prevent the work from rising with the punch a material distance.

The head B is provided with a socket in which is set the shank E, which is held in place by a screw e and carries a spindle E¹ 55 this mechanism being of usual construction,

e¹ being the punch attached to the spindle in the usual way. Around the spindle E¹ is a sleeve F¹ a portion of which is shaped to form a pulley F. Its lower end is shaped to form a tool holder in which is set the 60 countersink f which is of usual construction except that it has a passage through it so that it may be centered by, and rotate about, the punch e¹. The pulley F is operated by a belt F² passing around pulleys F³ 65 mounted on an axis in supports F⁴ on the table C. Above the pulley the countersink holder is grooved as at g and in the groove is a ring G which is pivotally mounted as at h³ in a strap lever H pivoted as at h to 70 hangers h¹ carried on the under side of the press B, this construction being such that the countersink holder and countersink will be freely rotated in the ring G about the tool holder E as an axis, and the ring and counter- 75 sink holder may be moved vertically with relation to the spindle on which it turns, by pressing down or raising the free end of the strap lever H.

In the operation of my device the strap 80 lever H being in its upper position as shown in Fig. 3, the press is brought down so that the punch drives its hole through the metal, which in Figs. 3 and 4 is shown as a flat plate D¹. In Fig. 1 the work is shown as 85 a corrugated plate such as is used as a foundation plate for a "safety tread" so called. The operator then depresses the outer end (not shown) of the strap lever H so as to bring the countersink down into 90 contact with the plate. It will be noted that the countersink is rotating all this time and when depressed it trims the opening which the punch has made in the plate and forms a countersink therein of any required 95 depth. When its work is finished the operator lifts the countersink holder and releases the head so that both tools are raised out of contact with the work, the clamp and overhang, if it be used stripping the work 100 off from the punch, and the clamp is raised, so that the plate D or D¹ may be moved the requisite distance for the next hole, when the operation is repeated of first punching a new hole and then countersinking it.

105 It is evident that my invention may be otherwise embodied, for as far as I know there has been no machine in which these two operations are carried on consecutively and without removal of the work. Other 110

tools may be substituted for the punch and countersink if desired as I do not mean to limit my invention to the tools named.

What I claim as my invention is:—

- 5 1. In a machine of the kind described, a vertically - reciprocating head, a punch mounted therein, a countersink mounted concentric with said punch to be reciprocated independently thereof, and means for 10 rotating said countersink.
2. In a machine of the kind described, a vertically - reciprocating head, a punch mounted therein, a countersink mounted concentric with said punch to be reciprocated therewith and also independently thereof, and means for rotating said 15 countersink about said punch.
3. In a machine of the kind described, a vertically - reciprocating head carrying a 20 spindle, a punch mounted in said spindle, a sleeve mounted concentric with said spindle, means for rotating said sleeve, means for moving said sleeve longitudinally with relation to said spindle comprising a 25 lever, and a rotary tool located in the end of said sleeve.
4. In a machine of the kind described, a

vertically - reciprocating head carrying a spindle, a punch mounted in said spindle, a sleeve mounted concentric with said spindle, 30 means for rotating said sleeve, means for moving said sleeve longitudinally with relation to said spindle comprising a lever pivoted to said head, said sleeve carrying a ring within which it may be rotated, said 35 ring being connected to said lever, and a rotary tool located in said sleeve.

5. In a machine of the kind described, a vertically - reciprocating head, a punch mounted therein, a countersink mounted 40 concentric with said punch to be reciprocated therewith and independently thereof, and means for rotating said countersink about said punch, said punch serving as a bearing for said countersink. 45

6. In a machine of the kind described, a vertically - reciprocating head carrying a tool holder, a second tool holder mounted concentrically with said first tool holder to be reciprocated therewith and reciprocated 50 and rotated independently thereof, and means for reciprocating and rotating it.

WILLIAM R. ORMES.
